UNITED STATES PATENT OFFICE.

EUGÈNE MARTIN, OF CANNES, FRANCE.

ELECTRIC SOLDERING APPARATUS.

1,354,986.

Specification of Letters Patent.

Patented Oct. 5, 1920.

Application filed April 3, 1920. Serial No. 372,231.

To all whom it may concern:

Be it known that I, EUGÈNE MARTIN, of Cannes, Alpes Maritimes, France, a citizen of the French Republic, have invented certain new and useful Improvements in Electric Soldering Apparatus, of which the following is a specification.

The object of this invention is to provide improved electric soldering apparatus enabling joints in the form of seams to be soldered by means of a continuous operation.

One embodiment of the invention is illustrated in the accompanying drawing, in which:—

Figure 1 is an elevation of the apparatus:

Figs. 2 and 3 show a detail thereof, to a larger scale, at two successive stages of the operation.

The apparatus shown comprises an electric transformer *t* for reducing the voltage of a direct or alternating current to the value required for soldering. Upon this transformer there is a bearing *m* for the pivot *o* of a double-armed lever or rocking beam *g* *g*¹, the arm *g*¹ of which is connected by a rod *h* to a lever *n*, the latter being pivoted at *s* to one of the feet of the transformer and being furnished with a treadle *p*. A spring *r* tends to hold the beam in the position shown in Fig. 1.

The arm *g* of the beam has a transverse slot *k* forming a slideway for a slide *d*, which carries a rack-bar *j* meshed with a pinion *i* working in a vertical slot above the slot. To the said pinion is fixed a lever *e*, for rotating it by hand and thus moving the slide. To the slide *d* there is pivoted a sector-shaped presser *b*, depending from the beam and having its cylindrical surface at the bottom. The presser *b* is electrically insulated from the slide. A link *f* attached to one side of the presser *b* is attached to the arm *g* at *l*.

Below the arm *g* there is a work support or bench *a* fixed to the transformer case but electrically insulated therefrom. One terminal of the transformer is connected to this bench by a cable *c*, and the other is connected to the slide *a* and presser *b* by a cable *c*¹. With the parts in the position shown in Fig. 1, the circuit is open by reason of the gap between the presser and the bench.

The work is placed upon the bench, as

shown at *x* in Figs. 2 and 3. For soldering a tube, the bench may be a narrow ledge on to which the tube can be slipped, as shown in Fig. 3.

For using the apparatus the hand-lever *e* is first pulled down to the left, as indicated by the arrow in Figs. 1 and 2, whereby the slide *d* is moved to the right, the link *f* causing the presser *b* to swing on its pivot toward the right, so that one end of the cylindrical presser surface is moved toward the bench, and the other is lifted away from the bench. The work is placed on the bench with the lap joint or seam extending lengthwise thereof, and one end of the joint just under the lowered end of the cylindrical presser surface, the treadle *p* being then depressed, so that the spring *r* is extended and the arm *g* lowered, the presser being placed upon the work (Fig. 2). By this means the electric circuit is closed, and the heat generated first softens and then fuses together the parts to be joined.

In the course of the soldering operation the operator maintains the pressure on the treadle, whereby the pressure is held against the work, but at the same time he rocks the hand-lever *c* over toward the right, as indicated by an arrow in Fig. 3, causing the slide *d* to move toward the left. The presser, being connected to the beam by the link *f*, is consequently caused to roll along the seam. The rate at which this rolling movement is performed is regulated by the operator according to the rate at which the current fuses the metal.

When the presser has completed its rolling movement, the link *f* being then nearly parallel with the beam, the treadle is released and the spring *r* quickly lifts the arm *g* and presser, thus breaking the circuit. The work is then pushed farther along the bench *a*, so that the right hand end of the presser surface can be lowered on to the joint at the place where the previous operation terminated.

The bench *a* and presser *b* are hollow and filled with water for cooling purposes. With high power, a pump may be provided for circulating the water.

The bench may be made adjustable, so that it can accommodate different kinds of work.

Means other than those illustrated may be used for the linear and rotary movements.

of the presser, and means other than a rocking beam may be used for moving the presser to and from the work.

In some cases the presser may be of such size that a single rolling operation will complete the seam, the arc of the pressing surface being equal in length to the seam.

What I claim as my invention and desire to secure by Letters Patent of the United States is:—

1. In electric soldering apparatus the combination of a bench, a slide, a carrier for said slide, a presser pivoted to said slide, having a curved working surface, means linking said pivoted presser to said carrier, means for moving said carrier to and from said bench, and means for supplying electric current to said presser.

2. In electric soldering apparatus, the combination of a bench, a slide, a carrier for said slide, means for reciprocating said slide on said carrier, a presser pivoted to said slide, having a curved working surface, means linking said pivoted presser to said carrier, means for moving said carrier to and from said bench, and means for supplying electric current to said presser.

3. In electric soldering apparatus the combination of a bench, a rocking beam, a slide reciprocable on one arm of said beam, a sector-shaped presser pivoted to said slide having a cylindrical working surface, a link connecting said presser to said beam, means

for rocking said beam, whereby said presser is movable to and from said bench and means for supplying electric current to said presser.

4. In electric soldering apparatus the combination of a bench, a rocking beam, a slide reciprocable on one arm of said beam, a sector-shaped presser pivoted to said slide having a cylindrical working surface, a link connecting said presser to said beam, means, including a treadle, for rocking said beam, whereby said presser is movable to and from said bench and means for supplying electric current to said presser. 40

5. In electric soldering apparatus the combination of a bench, a rocking beam, a slide reciprocable on one arm of said beam, a sector-shaped presser pivoted to said slide having a cylindrical working surface, a link connecting said presser to said beam, means for rocking said beam, whereby said presser is movable to and from said bench, a rack 55 fixed to said slide, a pinion meshed with said rack and mounted on said beam, means for rotating said pinion and means for supplying electric current to said presser.

In witness whereof I have signed this 60 specification in the presence of two witnesses.

EUGÈNE MARTIN.
